UNITED STATES PATENT OFFICE.

LOUIS H. ZANDERS, OF MALVERN, IOWA.

ARTICLE-CARRIER.

1,318,252.

Specification of Letters Patent. Patented Oct. 7, 1919.

Application filed January 3, 1918. Serial No. 210,168.

To all whom it may concern:

Be it known that I, LOUIS H. ZANDERS, a citizen of the United States, residing at Malvern, in the county of Mills and State of Iowa have invented certain new and useful Improvements in Article-Carriers, of which the following is a specification.

This invention relates to an article carrier for automobile running boards, the board 10 and the body of the automobile forming the bottom and rear wall of the carrier, and my device forming the front and end walls, and being collapsible, so that when not in use the said end and front walls lie flat on the 15 running board.

The invention consists in the novel features of construction hereinafter described, pointed out in the claims, and shown in the accompanying drawings, in which:

20 Figure 1 is a side elevation, the parts being in position for use.

Fig. 2 is a plan view, the front member and one end being in upright position, and one end folded down.

25 Fig. 3 is an end view, the running board being shown in dotted lines.

In the drawing A designates the running board. The device consists in two bars 1 which lie transversely across the running 30 board and at their front ends carry clamping members 2 with the usual screws 3. They are provided with transversely placed and perforated lugs 4 through which pass rods 5, one for each bar.

35 The end frames are hinged on these bars and comprise curved rear and top member 6 the vertical members 7, extending from the rods to the top members, and the horizontal members 8, these terms being descriptive 40 of the parts when lifted in position for use. The members 8 of each end member extend forwardly beyond the vertical members 7 to which they are secured.

Angled corner posts 9 are hinged to the 45 clamps 2 and connected by a rod 10. The lower portions of each post are cut away to form shoulders 9^a which coöperate with shoulders 2^a on the clamps, preventing outward movement of the front member, which 50 member consists of horizontal strips 11 ex-

tending from post to post, and the vertical strips 12.

The device being clamped to the running board the ends may be folded inwardly on the running board, and the side or front 55 member folded down on the ends. When the front member is lifted into vertical position it is stopped by the shoulders 9^a and 2^a coming into engagement, and then the ends may be lifted into vertical position, being 60 stopped by the projecting portions of the members 7 engaging the corner posts, as shown most clearly by the dotted portions of said members in Fig. 3.

The articles placed within the carrier will 65 prevent the walls from moving inwardly.

Suitcases and bundles can be readily carried in a device of this kind without strapping or danger of their falling from the running board. No locking devices are 70 required to hold the parts in position, and nothing has to be unlocked to hold the parts when they are not to be used.

What I claim is:

1. In a device of the kind described, 75 clamps adapted to be secured to a running board, a hinged front member carried by said clamps, hinged end members carried by the clamps, all of said members being adapted to fold inwardly, the end members 80 when in vertical position being stopped by the front member from further outward movement.

2. A device of the kind described comprising two parallel clamping bars, corner posts 85 of angle iron hinged thereto, strips connecting the posts and forming a front wall, rods carried by the clamps, end members hinged to the rods and having strips adapted when the end members are lifted into vertical position to engage the angled posts on their inner faces.

3. The combination with a running board, transversely arranged bars thereon carrying clamping members at their front ends, 95 lugs on the bars, rods mounted in the lugs, end members hinged on said rods, angled corner posts hinged to the clamping members, said members having shoulders, and the posts having coöoperating shoulders, and 100

a front member carried by the posts, as and for the purpose set forth.

4. The combination with a running board, bars lying transversely across the upper face 5 of said board, clamping members carried by the front ends of the bars, a hinged front member carried by the clamps, and hinged end members carried by the bars and con-

nected in substantially the plane of the front member, the end members being hinged to 10 fold toward each other on the running board, the front member being adapted to fold inwardly on said end members.

In testimony whereof I affix my signature.

LOUIS H. ZANDERS.
